ORDNANCE RECOIL APPARATUS

Filed July 9, 1919

2 Sheets-Sheet 2

UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

ORDNANCE RECOIL APPARATUS.

Application filed July 9, 1919. Serial No. 309,786.

To all whom it may concern:

Be it known that we, Sir ARTHUR TREVOR DAWSON and Sir GEORGE THOMAS BUCKHAM, both subjects of the King of Great Britain, 5 residing at Vickers House, Broadway, Westminster, in the county of London, England, have invented certain new and useful Improvements in or Relating to Ordnance Recoil Apparatus, of which the following is

10 a specification.

This invention relates to ordnance recoil apparatus and is particularly applicable to such apparatus in which the recoil or brake cylinder is connected to the gun and 15 the recoil or brake piston is connected to the gun cradle.

According to the present invention we provide a liquid reservoir or tank for maintaining the proper quantity of liquid in the 20 recoil or brake cylinder in spite of the loss which occurs during the firing of the gun and we connect this tank to the gun barrel at a suitable position in front of and above the gun trunnions so that liquid can flow by 25 gravity into the recoil cylinder at all angles of elevation of the gun, the action of gravity being assisted by the pressure in the tank due to the heating and consequent expansion 30 of the air therein above the liquid by the heat derived from the gun barrel as a result of firing. The tank may be of annular formation and may surround the gun barrel at a point a considerable distance in front of the trunnions; it may for convenience be 35 made in two portions (an inner and an outer portion) connected together by screw threads, the inner portion constituting the inner wall of the tank contiguous to the barrel and the outer portion constituting the 40 outer wall and the two end walls of the tank. The tank may be provided with keys or lateral projections adapted to slide in the usual guides formed in the cradle for the gun keys, thereby steadyng the forward 45 part of the gun barrel during recoil and run-out.

A hand operated isolating valve may be provided in the connection between the tank and the recoil cylinder for the purpose of 50 enabling communication between the tank and the cylinder to be cut off when so desired.

The forward end of the recoil cylinder may be provided with a valve (termed a 55 snifting valve) for the purpose of releasing

any air that may accumulate in the front end of the cylinder and interfere with the proper working of the recoil apparatus. This snifting valve is preferably actuated from a position at the rear of the gun shield by a 60 rod which operates at its forward end upon the valve and is connected at its rear end to a lever on the gun near the breech end thereof.

In order that the said invention may be 65 clearly understood and readily carried into effect we will describe the same more fully with reference to the accompanying drawings, in which:

Figure 1 is a side elevation with portions 70 in section showing a gun provided with a constructional form of our improvements.

Figure 2 is a front elevation of Figure 1.

Figure 3 is a vertical section showing a 75 window in the tank.

Figure 4 is a vertical section taken approximately on the line 4—4 of Figure 1 and viewed from the front, this figure being drawn to an enlarged scale.

Figure 5 is a horizontal section taken 80 approximately on the line 5—5 of Figures 1 and 4 and drawn to the same scale as Figure 4, and

Figure 6 is a side elevation of the rear part of a gun showing the position of the 85 lever for operating the snifting valve.

A is the gun and B is the cradle on which it slides during recoil and run-out. B' is the front cap of the cradle to which the rods B⁰, b⁰ of the recoil and recuperator pistons 90 are connected, the recoil and recuperator cylinders B⁰⁰, b⁰⁰ being connected to the usual lug A' on the breech end of the gun. C is the aforesaid liquid reservoir or tank which surrounds the gun barrel at a point a 95 considerable distance in front of the trunnions and is, in the construction shewn, made in two portions, namely an outer portion C' and an inner portion C² which are connected together by screw threads, the 100 inner portion C² forming the inner wall of the tank contiguous to the barrel and the outer portion C' forming the outer wall and the two end walls of the tank. C³ is one of the lateral keys or projections on the tank 105 which slide in the usual guides formed in the cradle for the keys on the gun barrel.

The inner portion C² of the tank is provided with rearwardly projecting keys of which one is shewn at c² in Figure 1, these keys 110

fitting in keyways or grooves cut in a shoulder a on the gun barrel against which the said inner portion is caused to bear by means of a collar a' which bears against the forward part of the inner portion C^2 of the tank and is connected by screw threads to the barrel, this collar being retained in its adjusted position by a grub screw a^2 or otherwise. The outer portion C' of the tank 5 is formed at its upper part with a filling hole closed in an air tight manner by a screw threaded plug c' so as to enable the heating of the contents of the tank, due to the firing of the gun, to exert air pressure on the liquid 10 to assist the action of gravity in replenishing the recoil cylinder with liquid from the tank. The rear wall of the said outer portion C' of the tank is provided at its lower part with a connection for a longitudinally disposed pipe c connected through the hand operated isolating valve c^x , which 15 is shewn as being of the screw-down type, to the rear part of the recoil or brake cylinder. This isolating valve is provided for 20 the purpose of enabling communication between the tank and the cylinder to be cut off when required, for example in the event of the tank becoming pierced by bullets or becoming otherwise damaged. The said 25 outer portion C' of the tank is also provided with a safety valve C^x and at one side with a window C^4 (Figure 3) through which the level of the liquid can be seen so as to ascertain when the tank should be replenished 30 with liquid. This window is made of plate glass and has behind it a metal plate c^4 of dished formation provided with a vertical slot and enameled or painted white on its outer surface so that the liquid which enters 35 between this plate and the window is viewed as a dark mass against a white background. The part of the outer portion C' of the tank beneath the filling hole may be formed with a downwardly projecting lip or flange c^9 40 (Figure 1) which prevents the tank from being filled to a greater height than the lower edge of this flange and so ensures that there shall always be a predetermined air space to allow for expansion of the liquid 45 under the influence of the heat from the barrel. To prevent undue heating of the contents of the tank an asbestos ring may be interposed between the barrel and the inner portion of the tank or an air space may, as 50 shewn in Figure 1, be provided in place of this asbestos ring.

D (Figure 5) is the aforesaid snifting valve arranged at the forward end of the recoil cylinder B^{90} in a hole communicating by a passage d (Figure 5) with the recoil cylinder for the purpose of releasing any air that may accumulate in the forward end of the cylinder. This accumulation of air results from the leakage of liquid from 55 the cylinder during the firing of the gun.

D' is the push rod for lifting this valve off its seat, the said rod at its forward end being arranged in close proximity to the stem of the valve D and at its rear end being connected to a lever D^2 pivoted on the gun near the breech end thereof and behind the gun shield D^3 .

What we claim and desire to secure by Letters Patent of the United States is:—

1. In ordnance, the combination with the gun barrel and the recoil cylinder, of a tank for containing liquid, means for establishing communication between said tank and said cylinder, means for connecting said tank to the gun barrel, and an isolating valve for cutting off communication between said tank and cylinder when required.

2. In ordnance, the combination with the gun barrel and the recoil cylinder, of a tank for containing liquid, means for establishing communication between said tank and said cylinder, means for connecting said tank to the gun barrel, a window in said tank and a plate having a white outer surface against which the liquid can be observed through the window as a dark mass.

3. In ordnance, the combination with the gun barrel, the gun cradle on which the barrel slides during its recoil and run-out movements, and the recoil cylinder, of a tank for containing liquid, means for establishing communication between said tank and said cylinder, means for connecting said tank to the barrel and means for slidably supporting said tank on the gun cradle.

4. In ordnance, the combination with the gun barrel, the gun cradle, the keys on said barrel sliding in guides in the cradle, and the recoil cylinder, of a tank for containing liquid, means for establishing communication between said tank and said cylinder, means for connecting said tank to the gun barrel, and lateral keys on said tank for engaging in the said guides formed in the cradle for the gun keys.

5. In ordnance, the combination with the gun barrel and the recoil cylinder, of an annular tank for containing liquid, said tank being composed of an inner portion constituting the inner wall of the tank and an outer portion constituting the outer wall and the two end walls of the tank, means for attaching said two portions together, means for establishing communication between said tank and said cylinder and means for connecting said tank to the gun barrel around the latter.

6. In ordnance, the combination with the gun barrel and the recoil cylinder, of an annular tank for containing liquid, said tank being composed of an inner portion constituting the inner wall of the tank and an outer portion constituting the outer wall and the two end walls of the tank, means for attaching said two portions together,

means for establishing communication between said tank and said cylinder, keys on said inner portion for engaging with grooves in the gun barrel and a screw 5 threaded collar engaging with screw threads on the barrel for holding said tank in place on the barrel.

7. In ordnance recoil apparatus, the combination with the recoil cylinder containing 10 liquid, of a valve for releasing to the atmosphere air that accumulates in the forward end of said cylinder.

8. In ordnance recoil apparatus, the combination with the recoil cylinder containing 15 liquid, of a valve for releasing to the atmosphere, air that accumulates in the forward end of said cylinder, and means for operating said valve from the breech end of the gun.

9. In ordnance having a shield, the combination with the recoil cylinder containing 20 liquid, of a valve for releasing to the atmosphere any air that accumulates in the forward end of said cylinder and means for operating said valve from a position behind 25 the gun shield.

10. In ordnance having a shield, the combination with the recoil cylinder containing 30 liquid, a spring controlled lift valve for releasing to the atmosphere air that accumulates in the forward end of said cylinder, a push rod for lifting said valve off its seat and a lever situated behind the gun shield for operating said rod.

In testimony whereof we affix our signatures.

ARTHUR TREVOR DAWSON.
GEORGE THOMAS BUCKHAM.
